TABULATING MACHINE

Robert E. Paris, New York, N. Y.

Application March 22, 1929, Serial No. 343,080

10 Claims. (Cl. 235—58)

This invention relates to controlling devices for tabulating machines, and particularly to devices for controlling the entering of debit, credit and net amounts or a plurality of such amounts at a single operation of the machine.

One of the principal objects of the invention is to provide a preliminary representation device wherein different parts may be moved to represent a debit and a credit thereby causing the entire device to represent the net amount.

Another object is to provide simplified means for sensing debits and credits from the punched record cards, whereby the capacity of the card may be greatly enlarged.

With these and other objects in view as will be apparent as the specification proceeds, the invention resides in certain novel construction and combination and arrangement of parts, the essential features of which are hereinafter fully described, particularly pointed out in the appended claims and illustrated in the accompanying drawings, in which:

Fig. 1 is a vertical sectional view showing the means for reading the data from the record card.

Fig. 2 is a vertical sectional view showing the numerical preliminary representation devices.

Fig. 3 is a view showing the side elevation of all of the contact plates of a section and indicating graphically how they combine and what they indicate.

Fig. 4 is a skeletonized front elevation of certain frames and shafts.

Fig. 5 is a fragment of a record card showing the numerical code punching.

Fig. 6 is a diagrammatic representation of a representative circuit.

Fig. 7 is a view similar to Fig. 2 but showing the alphabetical control devices.

Fig. 8 is a view similar to Fig. 1 but for the alphabetical control.

Fig. 9 is similar to Fig. 3 but for alphabetical control.

Fig. 10 is similar to Fig. 5 but for alphabetical and numerical code punching.

Fig. 11 is an end view of the commutator.

Fig. 11^a is an enlarged detail section of one denominational set of contact plates showing also one of the cooperative contactor bars, the proportions being exaggerated for the sake of clearness.

Fig. 12 is an enlarged fragmentary detail perspective view of the same.

Like characters of reference refer to like parts in all views.

Referring to the drawings, in detail, and in

particular to Figs. 1 and 2, 20 represents the tabulator-pin-guide plate of the well known construction, familiar in the commercial field as the Powers tabulator; and 21 represents the tabulator pins guided by said plate. In the machine as at present constituted and commercially known, there are twelve pins 21 in each column of which the nine pins toward the front of the machine control the setting of respective stops to enter the nine significant digits in the tabulator head. This is done by intermediate connections between the pins 21 and the known tabulator stops 22 which are mounted in the stop-basket 23.

However, in the present invention the pins 21 of each row, are divided into two sections, each section controlling, as desired, one or more rows of stops 22. By this is meant that an item punched in either the upper or lower half of the card may be entered in any desired zone of the tabulator or simultaneously in a plurality of zones, this being made possible by an intermediate "connection box" or device such as shown in my pending application Serial Number 324,427, and also indicated in Fig. 6 hereof. In order to do this, the record must be specially punched with combinational punchings. That is, each perforation no longer represents a single digit as in prior devices, but combined punchings represent the different digits according to a predetermined scheme and the upper and lower halves of the cards represent different data, although all the data on the card may be read at a single cycle of operation.

While the herein described means shows means for effecting control for alphabetical and symbol control, it may be well for the present to consider the devices only in their digit control and later in this description describe the extension to alphabetical and symbol control.

As shown in Fig. 5, the zones of punching have been reallocated so that the positions formerly used for 12, 11, 0 and 1, may now, by combinational punchings, represent 1 to 9, and the positions formerly used for the digits 4 to 7, inclusive, may now, by combinational punchings, represent 1 to 9. Thus the data capacity of the card is doubled. The code punchings for numerals as shown are as follows: a punch in the position formerly allotted to "12" now represents "9"; combination of perforations at positions "12" and "11" now represents "8"; combination of perforations at positions "11" and "0" now represents "7"; combination of perforations at positions "0" and "1" now represents "6"; combination of perforations at "12" and "1" now represents "5", a single perforation at position "11" now rep-

resents "4"; combination of perforations at "12" and "0" now represents "3"; combination of perforations at "11" and "1" now represents "2"; a single perforation in the former "0" position now represents "1" and a single perforation in the "1" position represents "0". In like manner the lower half of the card is coded as follows:

10	Punchings in the positions formerly designated as below	Now represent digits as shown below
15	4 4 and 5 5 and 6 6 and 7 4 and 7 5 4 and 6 5 and 7 6 7	9 8 7 6 5 4 3 2 1 0
20		

It will be recalled from the known Powers tabulator as commercially on the market, that wherever a perforation occurs in the data card, 25 a pin 21 will be raised during the cycle of operation in which the card is passed through the machine. But in the known structure only one series or line of data is read from each data card, whereas in the present invention it is necessary 30 to provide means for sensing two series and conducting the sensed amount from each series to a different portion of the tabulator head. Such means is provided and will now be set forth.

35 *Sensing means*

It may be well at this point to make reference to my prior application Serial Number 324,427 of which the present device is in some respects a modification and extension.

40 On the edge of the pin plate 20 there have been placed the numerals "0" to "12", inclusive, indicating the values of the pins 21 in the Powers machine as at present on the market. Directly over the pins 21 in the 12, 11, 0, 1, 4, 5, 6, 45 and 7 positions are respective contactor bars which are indicated respectively as 200, 201, 202, 203, 200A, 201A, 202A and 203A, the first four bars being raisable by the pins co-operative with one half of the record card and the second four 50 by the pins co-operative with the other half of the record card. Inasmuch as each of these eight bars rests with its lower end immediately over a respective pin 21, it is obvious that each bar has an upper and a lower position in one or the 55 other of which the bar will stand according to whether its pin 21 is raised or lowered. It will be remembered that a perforation in a record card permits raising of the respective pin 21 and consequently in the present construction will 60 result in the raising of the respective contactor bar. It will be understood, of course, that there is one series of eight contactor bars for each column of analyzing pins 21, the several series being duplicates of each other.

65 Each of the contactor bars 200, 201, 202, and 203 is provided with a respective upper laterally extending contactor or brush 204 and a respective lower laterally extending contactor or brush 205; and similarly the bars 200A, 201A, 202A, and 203A 70 have upper and lower contactors 204A and 205A, the contactors 204 and 205 being arranged in different horizontal planes from 204A and 205A. The several brushes 204, 205, 204A and 205A are insulated from their supporting bars.

75 Universal bars 24, 25, 26 and 27 are supported

and guided in slots 28 in the framework 29. Rods 24, 25, 26, and 27 are either made of insulating material or are suitably insulated from parts with which they cooperate. Secured to rods 24, 25, 26 and 27 and movable therewith are a plurality of vertically disposed carriers or tie and spacing members 30 and 31 preferably made of insulating material, members 30 extending above the rod 24 for a purpose to be presently set forth. Mounted on the rods 24, 25, 26 and 27 are two series of 10 contact carriers, one series above the other. Each series of contact carriers consists of five thin contact plates insulated from each other in any desired manner and all secured together and held between spacers 30 and 31 on rods 24, 25, 26 and 15 27. The five plates of each upper series are indicated respectively by reference numerals 208, 209, 210, 211 and 212 while those of the lower series are indicated at 208A, 209A, 210A, 211A and 212A, the plates 208 and 212 of the upper series 20 and 208A and 212A of the lower series being the outer plates of these series.

And now the purpose of these series of plates will be considered, bearing in mind that those having an "A" as part of the reference characters 25 are co-operative with those contactor bars having an "A" as part of the reference characters. Current is conducted to the contact carrier 212 or 212A at one side of each series of plates by any desired means such as spring brushes 213 and 30 213A, and brushes 214 and 214A contacting the carriers 208 and 208A at the other side of the series are provided with connections (later fully described) leading to desired add and subtract electro-magnets 32 and 33. Thus when a circuit 35 is completed through the five plates of any series, the correlated magnet or magnets 32 and/or 33 are operated to stop the correlated preliminary representation slide so as to control entering the digit represented by the position of the series of 40 contact carriers at the time of completing such circuit. The means by which the carrier plates are connected at the proper instant includes contacts on the carrier plates and the brushes 204 and 205 and/or 204A and 205A. This means of 45 connection will now be described.

As shown in Fig. 3 the plates 208—212 and 208A—212A are formed with upper contact fingers 215 and lower contact fingers 216; and the five plates of a series are held between plates 217 of 50 insulating material of sufficient breadth to permit exposure of the ends only of the fingers 215 and 216 to the action of the brushes 204, 205, 204A, and 205A. Normally, the brushes 204, 205, 204A and 205A are all down, so that the brushes 204 and 55 204A would be in position to contact the several contacts 215 as they are moved across the brushes. But if any of the bars 200 to 203 and 200A to 203A is raised, then its brush 204 or 204A is raised out of effective relation to the contacts 215, and its 60 brush 205 and 205A is raised into effective relation to the contacts 216.

It may be well at this point to consider Fig. 3 somewhat more in detail. It will be noted that the contact bars have been divided into zones by 65 vertical lines, the zones being indicated by the letters *a* to *m* and *x* to *z*. The width of a zone is the distance between the centers of the bars 200 to 203 or 200A to 203A. The contacts 215 and 216 within these various zones have been primed with 70 the letter of that zone. These contacts have been so arranged that for each of the above described code punchings of the card there will be only one position at which the circuit will be closed through the five contact bars and that position will be such 75

that the operation of the correlated magnet 32 or 33 will stop the respective slide according to such code punching. The bars 208—212 have been shown here as identical with bars 208A—212A which is correct as far as the relation of the contacts is concerned but of course, the bars themselves are made with the entire series of contacts arranged to co-act with the respective brushes as clearly shown in Figs. 1 and 5.

10 The several slide bars 200—203, 200A—203A are supported in upright position and guided in slots in plates 34 and 35 and normally rest upon the upper tabulator pinplate 20.

Considering now the means for causing contact plates 208—212 and 208A—212A to traverse the brushes 204—205 and 204A—205A, 37 represents a rotating drive shaft of the tabulator. Upon the end of this shaft 37 is pinned a disk 38 carrying a laterally extending pin 39 which rides in a slot 40 formed in a rocker 41 pivoted at 42 and connected by a link 43 to one end of an arm 44, the other end of which is fast on a rock-shaft 45. This rock shaft 45 carries a pair of depending arms 46 to which are pivoted links 47 formed with slots 48 thru which the rod 25 extends. Springs 49 anchored at one end to the links 47 and at the other to the rod 25 tend to constantly hold such rod in the left-hand ends of slots 48 as viewed in Fig. 1.

It will now be apparent that rotation of shaft 37 will cause rotation of disk 38 which will cause pin 39 to effect rocking of rocker 41, whereby link 43 will be caused to rock arm 44, shaft 45 and depending arms 46. This causes reciprocation of links 47 and rod 25. Rods 24, 25, 26, and 27 together with the tie and spacing members 30 and 31 and the several series of contact plates form a unit so that reciprocation of rod 25 effects reciprocation of all of the contact plates so as to traverse the several brushes 213, 214, 213A, 214A.

40 Turning next to the circuits closed by the completing of the connection from one outside plate to the other of any series of contact plates 208—212 and 208A—212A, a suitable source of electric energy is indicated at 50 from which current is passed over a lead 51 to a brush 52 which contacts a rotary commutator body 53 mounted on shaft 54 for rotation thereby and having a contact strip 55. A second brush 55 also contacts the periphery of commutator 53 and is connected by a lead 56 and branches to the several spring brushes 213, 213A, 214 and 214A. Brushes 213, 213A, 214 and 214A are supported on through rods 57, and while the rods 57 of brushes 213, 213A need not be of insulating material, the rods 57 of brushes 214, 55 214A must be of insulating material or suitably insulated from the brushes mounted thereon. Each brush 214, 214A is connected by a respective lead 58 to a respective cross rod 59 of the connection box 60; and each cross rod 59 may be connected by means of sliding connectors 61 and 62 to any one or plurality of vertical strips 63 and 64, elements 61 and 63 controlling addition, and 62 and 64 controlling subtraction. The connection box 60 is fully described in my pending application Ser. No. 324,427 filed December 7, 1928, to which reference may be had for a more complete description. Each of the vertical strips 63 is connected to one side of a respective adding magnet 32 by a lead 65; and similarly, each of the strips 64 is connected to one side of a respective subtracting magnet 33 by a lead 66. The other sides of all of the magnets 32 and 33 are grounded to a lead 67 back to the source 50.

In order to hold the several magnets 32 and 33 energized after the same have been energized

and during such portion of cycle as is necessary, even though the energizing contacts 215 and 216 may have passed out of energizing position, I provide what I term "holding" circuits for these magnets. A third brush 68 contacts the commutator disk 53, and a portion of the contact strip 54 is notched at 69 so that this brush will not contact strip 54 until shortly after brushes 53 and 55, for a purpose hereinafter set forth in connection with alphabetical control. For present purposes it is enough to say that all three brushes are effective whenever a digit control is effected by contacts 215 and 216. This brush 68 is connected by a lead 70 and branches to the armature 71 of each and every magnet 32 and 33. The positive or inlet side of each magnet 32 and 33 is connected to a respective contact 72 positioned to be engaged by the armature 71 of the respective magnet when in closed position. Hence when once the armature of a magnet 32 or 33 is closed it will be held closed by the circuit from 50 thru 51, 52, 54, 68, 70, 71, 72, 32 or 33, and 67, until this circuit is broken by the rotation of commutator disk 53 sufficiently to bring contact strip 54 out of engagement with brushes 52 and 68. During this time the mechanism of the tabulator head has completed its recording of the required amounts.

Considering a concrete example, presume that it is desired to enter a credit of 29 and a debit 30 of 15 and to automatically determine and enter the net amount of 14; and that the credit is entered on the top half of the card (usually devoted to "12" to "3") and the debit on the lower half of the card (usually devoted to "4" to "9").

The card for this example therefore has a tens column punched with perforations in the "11" and "1" positions to indicate the tens credit entry "2", and with a single perforation in the "0" position to indicate the tens debit entry "1". The units column is punched in the "12" position to indicate the units credit entry "9" and in the "4" and "7" positions to indicate the units debit entry "5". When this card is fed into the machine, it will cause the raising of the bars 201, 203, 202A 40 associated with the tens denominational contact carriers 208 to 212 and 208A to 212A of one zone; and the bars 200, 200A and 203A associated with the units denominational contact carriers of the same zone. (It will be remembered that the columns of a punch card are divided into vertical zones according to the requirements of the business).

An inspection of Fig. 3 will readily show that when the tens bars 208—212 have moved far enough for the contacts 216h of plates 211 and 212 to have come in line with bar 203, contacts 215i of plates 208 and 209 will be in line with bar 202, contacts 216j of plates 209 and 210 will be in line with bar 201, and contacts 215k of plates 210 and 211 will be in line with bar 200. Now it will be recalled that bars 201 and 203 have been raised and that bars 200 and 202 have remained down, so that the brushes 205 of bars 201 and 203 and brushes 204 of bars 200 and 202 bridge 65 the contacts 216j, 216h, 215k and 215i respectively, whereby the circuit is closed from plate 208 to 212, and the correlated magnet 32 is operated to stop the respective preliminary representation slide at the "2" position as will be presently set forth more fully. At no other position of these bars 208—212 during their excursion will the contacts and brushes cause the completing of this circuit with bars 200—203 in this relation to each other.

Proceeding with our example, the tens bars 208A—212A during their excursion eventually bring the contacts 215i of bars 208A and 209A into contact with the brush 204 of bar 203A and 5 at this time contacts 216j of bars 209A and 210A meet brush 205 of bar 202A (which has been raised due to a perforation in the "6" position), contacts 215k of bars 210A and 211A meet brush 204 of bar 201A and contacts 215l of bars 211A 10 and 212A meet brush 204 of bar 200A. The circuit is thus completed and the correlated magnet 33 is operated to effect stopping of the respective subtraction slide in its "1" position.

In like manner the units bars 208 to 212 and 15 208A to 212A are bridged when they arrive at the "9" and "5" positions respectively and thus the credit and debit amounts have been set up.

Locking mechanism

20 When bars 200—203 and 200A—203A have been raised, means are provided for locking raised bars in raised position and lowered bars in lowered position. For this purpose, each of these bars is provided with an upper notch 73 and a 25 lower notch 74. The upwardly extending portions of members 30 hereinbefore mentioned, normally contact a cross rod 75 and hold it to the right in Fig. 1 against the tension of springs 76. This rod 75 together with another rod 77 and 30 a plurality of cross strips 78 form a locking frame. This locking frame is supported and guided by projecting the ends of rods 75 and 77 through short slots in the framework. Each cross strip 78 is provided with lateral pins 79 for engagement with the notches 73 or 74 of the bars 200—203 and 200A—203A. Preferably there is only one bar 78 for each two rows of bars 200—203 and 200A—203A, the pins 79 projecting on both sides of bars 78 so as to co-act with the 40 adjacent bars 200—203 and 200A—203A on each side of each bar 78. As soon as the spacers 30 start their excursion toward the left in Fig. 1, the locking frame is permitted to follow up until its pins 79 engage the notches 73 of all lowered 45 bars and the notches 74 of all raised bars. Upon the return of spacers 30 the locking frame is forced back to ineffective position, and the raised bars 200—203 or 200A—203A drop back to lowered position. Thus springs 76 offer no resistance to 50 bars 200—203 and 200A—203A while being raised and lowered, but hold them in proper position during the required portion of the cycle.

Setting up the net

55 Having considered in the foregoing pages how the debit and credit punchings in a card control the energizing of adding magnets 32 and subtracting magnets 33, the means controlled by such magnets for producing the net balance will 60 now be discussed.

Referring particularly to Fig. 2, there is provided a plurality of adding or credit magnets 32 having armatures 71 and stops 80 similar to the magnets 52, armatures 104 and stops 105 of my 65 said prior application. There is also provided a plurality of subtracting or debit magnets 33 having armatures 71 and stops 81, each of the latter having a guide pin 82 riding in a slot 83 in a respective guide bar 84. Each stop rod 81 70 has a laterally extending portion 85 at its upper end. Each magnet 32 is connected in circuit through the connection box 60 with such bars 208—212, 208A—212A as are allotted to the desired denominations of the desired credit entry, so that bridging of the respective bars causes

simultaneous operation of the respective magnet 32; and in like manner each magnet 33 is connected in circuit with such bars 208—212, 208A—212A as are allotted to the desired denominations of the desired debit entry, so that bridging of the respective bars causes simultaneous operation of the respective magnets 33, by means above described.

While it has been considered in the respective example under consideration that the debit and credit items are in the same zone on the card, it is to be understood that they may be in different zones and that credits may be on either the upper or lower half of the card or both and similarly with debits. Of course, the debits and 15 credits which are to be related must be caused to control correlated circuits by a connection box as shown in my said application and indicated herein at 60 or by directly creating such circuits in any desired manner such as that used in the 20 "Hollerith" type of tabulator or in any other suitable manner.

The several bars 84 are mounted on two cross-rods 86 and 87 and spaced apart in any suitable manner, there being one bar 84 for each row of 25 stops 22. The bars 84 are positioned directly beneath the respective rows of stops 22. Slidably mounted on each bar 84 is a slider formed with two side plates 88, spaced apart at the bottom by a bar 89 to which the plates 88 are riveted. 30 The bar 89 is formed with stop teeth 90 to cooperate with the associated stop rod 80; and is formed with a spring anchor 91 to which one end of a spring 92 is secured. The other end of spring 92 is anchored to any suitable stationary 35 part such as a rod 93, and tends constantly to draw the plates 88 toward the right as seen in Fig. 2.

The plates 88 rise on each side of the respective bars 84, and the plates are formed with ears 40 94 or other suitable means, passing across and riding upon the respective bars 84. The plates 88 extend upwardly so that each pair of plates forms a guideway for a respective subtraction 45 slide 95. Each subtraction slide 95 is formed with a downwardly extending portion 96 which rides on the respective bar 84, and also is provided with a pin 97 which extends into a bayonet-slot 98 in plates 88 and formed so as to provide a stop shoulder 99. The upper part of slot 98 is 50 ten spaces long and the lower part is eleven spaces long. The upper edge of each subtraction slide 95 is formed with a plurality of stop teeth or shoulders 100, the zero stop being considerably higher than the others. Each subtraction slide 55 95 is also formed with an abutment shoulder 101, and an upwardly extending shoulder 102.

Springs 104 hold up the right-hand ends (as seen in Fig. 2) of slides 95 and tend constantly to hold the shoulders 101 against a universal rod 60 105 and to hold pins 97 in line with shoulders 99. Rod 105 forms part of a frame having side bars 106 and a cross-tie rod 107 which frame is reciprocated at each cycle of the machine by links 108 pivotally connected to 105 and at 109 to upper 65 arms 110 secured to and rocked by shaft 45. It will thus be seen that universal bar 105 not only controls movement of slider 95, but, through pins 97, also controls movement of the slides 88 which are moved back to normal and retained there by 70 pins 97. The frame 105—106—107 is supported and guided by extending bar 105 into slots in the framework and by forming the members 106 L-shaped and extending studs 111 through parallel with 107 and in the same horizontal plane as 75

105, so they may ride in the same slots somewhat extended.

Above the slides 95 are respective guide bars or rails 112 which are mounted at one end on the stationary rod 113 and at the other on the movable rod 114. Mounted on one side of each bar 112 is a summation slide 115 which is held to and guided on the bar 112 by bent over tabs or ears 116. This slide 115 is also formed with an upwardly extending stop-setting finger 117, an elevated portion 118, an inclined cam face 119, a shoulder 120 and a restricted portion 121. Each slide 115 also carries a hook 122 pivoted to its lower edge and held up by the correlated portion 85 of a stop 84, and in the plane of the correlated subtraction slide 95 and adapted to be dropped into engagement with the teeth 100 thereof. Also the lower edge of each slide 115 is formed with a finger 123 which is bent into the plane of the shoulder 102 of its own denominational slider 95, and a finger 124 bent into the plane of the higher order subtraction slider 95. A universal carrying bar 125 extends above all of the rails 112.

25 Mounted on each rail 112 is a secondary slider 126, the same being arranged along the side of the rail 112 opposite to slider 115 and having bent over ears 127 and 128, the latter extending into the cutaway portion 121 of the slider 115 on the same rail 112. The restricted portion 121 is of such extent that from the shoulder 120 to the ear 116 is slightly more than ten spaces of movement, that is, the distance is equal to ten times the distance between centers of the stops 22 plus the width of ear 128. Thus it will be seen that slider 115 after it has moved ten spaces will pick up the secondary slider 126 and carry it with it. The secondary slider 126 is also provided with a stop-raising finger 129 similar to the finger 117 of the slider 115.

Negative carrying

Whenever slider 115 is moved more than ten spaces it is necessary to deduct one from the next higher slider and this is accomplished as follows:

Presuming that 2 has been added this will mean that slider 88 has moved to bring the eighth tooth 90 (the second tooth from the left) 50 into co-operative relation with stop 80 before the stop 80 will have stopped it, the slider 95 also moving the same distance and then moving until its pin 97 strikes the shoulder 99. If 8 is to be subtracted in this column, the magnet 83 of that 55 column will lower the hook 122 into engagement with the eighth tooth of slider 95 (the second tooth from the right). Slider 115 will thus be carried sixteen spaces thereby moving its finger 117 out of the field of stops 22, but it will have 60 picked up the secondary slider 126 and moved it six spaces so that it will stand under the 4 pin. When slider 115 moves from its tenth step to its eleventh step its incline 119 has engaged the universal bar 125 thereby depressing the right 65 hand end of slider 115 and its finger 124 will have pressed down the right hand end of the next higher slider 95 so that the pin 97 of the latter comes below the stop 99 of its member 88 and this next higher slider 95 will, therefore, 70 move one additional step so that the cooperating finger 117 or 129 will be moved to the next adjacent stop 22 thereby deducting one from this next higher slider.

In order to rock the frame comprising universal bar 114 and members 112 so as to effect

raising of all of the desired stops 22, the outer member 112 is provided with a roller 130 which is engaged and raised by a cam portion or lug 131 on member 108 as it nears the end of its excursion to the right in Fig. 1.

Pursuing our problem 29-15-14, it will be seen that the tens slide 88 moved far enough before being stopped to have brought element 117 under the "2" pin 22 if no subtraction were being done. But as "1" was to be subtracted, hook 10 122 became effective on the "1" shoulder 100 and when slider 95 completes its excursion, it will have moved the slider 115 to bring its element 117 under the "1" pin 22 of the correlated row. In like manner, in the units column, slider 88 15 will have stopped at the "9" tooth (first to the right), and hook 122 will have engaged the "5" shoulder 100 so that when this slider 95 completes its movement the cooperative slide 115 will have its element 117 under the "4" pin 22 of 20 that row. It will be easier to understand this action if it is remembered that slider 115 is moved only by slider 95 and only after hook 122 becomes effective, while slider 88 is merely a limiting means for determining the excursion of slider 95. 25

Now consider the converse proposition 15-29=-14. The units hook 122 becomes effective on the "9" shoulder 100 and moves the slide 115 in unison with the slide 88 until the element 115 is under the "5" stop 22, at which time slide 30 88 is stopped and slide 95 continues to move slide 115 ten spaces further thereby bringing element 129 under pin "5" (the complement of the digit "6" of the result) and effecting a negative carry. In the tens column the slides 88 and 95 move 35 idly until hook 122 is brought down into engagement with the "2" shoulder 100 after which all three slides move one space in unison bringing element 117 under the "9" pin, when slide 88 is stopped. Slide 95 now moves eleven spaces by 40 virtue of the carry from the units column thereby bringing finger 129 under the "8" pin (the complement of the digit "1" of the result) and effects a carry, and as each higher slide 115 will, therefore, move eleven spaces, "9" will be 45 set up in each of the higher orders so that the negative amount "16" will be positively entered complementally, thereby effecting correct result.

Alphabetical control

50

It is at times necessary to devote a portion of the tabulator to the printing of alphabetical or symbolic matter, and in the Powers tabulator as at present constituted, an alphabetical sector is used comprising two parts, one of which is 55 brought into action by a perforation in the card controlling the zero stop 22. In the present instance, a perforation in the "3" position or in the "9" position controls means for operating the zero pin 22 so as to release the second portion of the 60 alphabetical sector. The means whereby this is accomplished is as follows:

The alphabetical arrangement of types used in the standard Powers alphabetical tabulators has 65 been accepted, the same being set forth in United States Patent #1,684,001. However, the code punching has been changed so as to punch two lines of matter on a single card although this matter may be transcribed as a single line by the 70 tabulator. A desirable alphabetical code punching is shown in Fig. 10. It is also necessary in increasing the capacity thus to utilize six contact carrying bars and six brush carriers. The specific mechanism for alphabetical work is best 75

shown in Figs. 7, 8, 9 and 10 and is constructed as follows:

For each column of the card devoted to alphabetical or symbol control, there are provided two series of six contact carriers each indicated as 300, 301, 302, 303, 304, 305, and 300A, 301A, 302A, 303A, 304A, 305A, respectively. As in mere numerical control, the two series are similar being merely spaced so as to bring their contacts 215 and 216 into cooperative relation with their respective brush carriers. The alphabetical brush carriers are indicated at 306, 307, 308, 309, 310, 311 and 306A 307A, 308A, 309A, 310A, 311A and carry brushes 204, 205, 204A and 205A, carriers 15 311 and 311A being provided only with brushes 205A as their only function is to bridge directly across from plate 300 to 311 or from 300A to 311A whenever a punch occurs in the "3" or the "9" position. The elements 300—305, 300A—305A, 20 306—311 and 306A—311A are constructed and operate the same as similar parts of the numerical mechanism hereinbefore described. Consequently, associated elements which are duplicates of those used in the numerical mechanism are given 25 the same reference characters in the drawings.

The bars 300—305 or 300A—305A are connected by means of the connection box 60 to respective magnets 230 provided with armatures 231 each of which is connected by a link 232 with a bell-30 crank 233 pivoted on a rod 234. The lower arm of this bell-crank is provided with a slot 235 in which rides a pin 236 of a vertically movable bar 237 provided at its upper end with a turned over finger 238 and intermediate its ends with a stop pin 35 239. The mechanism is so timed that when one of the magnets 230 is operated by the bridging of the contacts 216X (i. e. where there is a perforation in the "3" or "9" position) the brush 68 will be in the notched out portion 69 of the 40 commutator and consequently this magnet will be operated and then let go as its holding-circuit will not have been closed by contact of brush 68 with the contact strip 54. The vertically movable bar connected with this particular magnet will, 45 therefore, be raised and then lowered by a spring 2370, which will set mechanism for operating the zero stop 22 for releasing the alphabetical sector, which mechanism will now be set forth.

In that unit of the mechanism devoted to alphabetical work each of the sliders 880 mounted on the rails 84 is formed in a single piece having ears 240 slidably securing the respective slider 880 to the respective rail 84 and formed with teeth 90 and with an upwardly extending finger 241 carrying a pin 242 extending through a slot 243 in the depending finger 244 of a slider 245 mounted on a respective rail 112. The slider 245 is formed with ears 246 embracing and movably securing the slide 245 to the rail 112, and carries 50 a stop-lifting finger 247. Also mounted on each rail 112 is a second slider 248 provided with ears 249 which embrace the rail 112 in such manner that the slider 248 is movable along the rail and cross-wise of the rail so as to render its stop-raising finger 250 effective for raising the zero stop 22 of the tabulator. The slider 248 is provided with an upwardly projecting hook element 251 which is adapted to engage and hook into a retaining ledge 252 formed on a member 253 55 carried by the guide plate 254 of the pins 22. The slider 248 is also provided with an upwardly extending finger 255 to which one end of a diagonally disposed spring 256 is attached, the other of the spring being attached to the member 253 as 60 shown in Fig. 8. The spring 256, therefore, tends 75

constantly to pull the slider 248 toward the right in Fig. 8 and also to keep the free end of the slider down in contact with its rail 112. The connected fingers 241 and 244, of sliders 880 and 245 contact bar 105, and slider 245 engages the upstanding spring finger 255 to hold the slider 248 normally to the left. 5

When, however, a punch occurs in a position other than "3" or "9" position, the required magnet 230 is operated after brush 68 has left notch 10 69 and the "holding-circuit" holds the magnet energized, the pin 239 having engaged the proper tooth 90, and being held so as to maintain finger 247 under the proper stop 22. Of course where there are double punchings, both the stop 250 and 15 stop 247 will be brought to operative positions and will raise respective stops 22 when the universal bar 114 is raised. It may be well at this point to note that when the stop finger 250 is to be set for active work (i. e. when a hole is punched 20 in "3" or "9" position), the bar 237 is operated at approximately the instant that rod 105 starts its rearward excursion. This rocks slide 248 slightly so as to bring hook 251 into position to hook on ledge 252. As bar 105 is moving rear- 25 wardly, spring 256 draws hook 251 onto ledge 252. It will be remembered that the "holding circuit" is not effective at this time, and consequently member 237 drops back to lowered condition before any tooth 90 arrives at pin 239. The operation 30 progresses and at some point in the travel of slides 880 and 245, depending on the secondary aperture or apertures of the combinational punchings, the member 237 is again operated, stopping these slides with finger 247 under the 35 desired pin 22. After the several fingers 247 and 250 are set, bar 114 is raised as in Fig. 1 and in any column where both fingers 247 and 250 are active the "0" pin and one of the other pins will be raised with consequent control of the tabulator 40 head as is well-known in the art. Thus means are provided for both numerical and alphabetical work.

While I have described what I consider to be the most desirable embodiment of my invention, 45 it is obvious that many changes could be made without departing from the spirit of my invention, and I, therefore, do not limit myself to the exact construction shown nor to anything less than the whole of my invention as hereinbefore 50 described, and as hereinafter claimed.

I claim:—

1. In a machine of the class described including record controlled sensing pins and tabulation controlling stops, the combination of a preliminary representation device controllable from certain of said pins to represent a credit, and an associated preliminary representation device controllable from certain of said pins in accordance with a debit, and means for automatically setting up said 60 tabulation controlling stops in accordance with the net result obtained by said preliminary representation devices.

2. In a machine of the class described the combination of a credit slide, a debit slide operatively 65 related thereto, and independent record-controlled means including electric circuits for controlling said credit and debit slides and setting up a preliminary representation of the net amount. 70

3. In a machine of the class described the combination of a movable element, means for moving said element, record controlled means for differentially arresting movement of said element, of a second movable element, means for moving said 75

second movable element a distance controlled by the differential movement of said first named element, a third movable element, and record controlled means for operatively engaging at different points the third movable element with the second movable elements whereby said third movable element may be caused to set up a mechanical representation of the combined record-controls.

4. In a machine of the class described the combination of a plurality of denominational credit elements; a plurality of denominational debit elements, each operatively associated with a respective one of said credit elements; a plurality of net or balance elements each operatively associated with a respective one of said credit and debit elements; carrying means for effecting the carrying from a net or balance element of one denomination to a net or balance element of another denomination and tabulator stops settable by said net or balance elements.

5. The combination of a series of movable contact plates secured together to operate as a unit and also being insulated from each other and carrying contacts, means including settable contactors for bridging the contacts from one to another of said plates so as to complete a circuit therethrough, tabulator controlling mechanism cooperative with said plates, and means for moving said plates relatively to said settable contactors.

6. In a machine of the class described, the combination of a series of movable contact plates secured together to operate as a unit and also being insulated from each other and carrying contacts, contactor carriers adapted to connect a contact on one of said plates with a contact on another of said plates; record controlled means for operating said contactor carriers in accordance with a predetermined code, means for moving said contact carriers and contactor carriers relatively to each other, and tabulator controlling means operatively associated with said contact plates.

7. In a machine of the class described the combination of a preliminary representation member; a second preliminary representation member, movable relatively to the first said member and controllable thereby and carrying means including a pin on one of said members and movable for permitting movement of one of said members relatively to the other of said members so as to permit a variable amount of relative movement between said members.

8. The combination of a slider, record controlled means for limiting movement thereof, a second slider movable in unison with and relatively to the first said slider, a third slider, means for coupling the second and third sliders, and means controlled by the third slider for controlling the amount of relative movement between the first and second sliders.

9. In a machine of the class described including record-controlled sensing pins and tabulation controlling stops, a plurality of electrical contactors arranged for individual movement by said pins in a denominational column, a plurality of electric contacts for each column, means for moving relatively said contactors and said contacts to bring the contacts in a column successively into engagement with the contactors of said column, and means controllable by the coaction of said contactors and contacts for controlling said stops.

10. In a machine of the class described including record-controlled sensing pins and tabulation controlling stops, a plurality of electrical contactors arranged for individual movement by said pins in a denominational column, a plurality of electric contacts for each column, means for moving relatively said contactors and contacts the same distance at each cycle of operation to bring the contacts in a column successively into engagement with the contactors of said column, and a stop controlling electrical circuit completed at different points in the movement of the contacts for effecting different representations.

ROBERT E. PARIS.
